ABSTRACT OF THE DISCLOSURE

A gas turbine by-pass engine has a compressor means, a combustion means and a turbine means, a freely rotatable main fan extends completely across the by-pass duct and a secondary fan is positioned upstream of the main fan and extends only partially across the by-pass duct, the secondary fan being driven by the turbine means.

This invention relates to gas turbine by-pass engines in which a fan is mounted in the by-pass duct of the engine.

According to the present invention there is provided a gas turbine by-pass engine having compressor means, combustion means and turbine means, a freely rotatable main fan extending completely across the by-pass duct and a rotatable secondary fan positioned upstream of the main fan and extending only partially across the by-pass duct, the secondary fan being driven by the turbine means and being arranged to drive the main fan.

Preferably the tip speed of both the main fan and secondary fan is arranged to give a blade relative inlet Mach number always less than unity. The main fan may be arranged to be mounted for free rotation on a compressor casing.

The invention will now be more particularly described with reference to the accompanying drawings in which:

FIG. 1 shows a diagrammatic representation of one form of gas turbine by-pass engine according to the present invention and

FIG. 2 shows a modified form of the engine shown in FIG. 1.

In FIG. 1 a gas turbine by-pass engine consists of compressor means 10 combustion means 12 and turbine means 14.

The compressor means 10 has a multistage compressor 16 driven by a turbine 18 through a shaft 20 and a conventional high pressure compressor 22 driven by a turbine 24 through a shaft 26. A main fan 28 extends completely across the by-pass duct 30 of the engine and is mounted on bearings 50 which are located on a casing 32 of the compressor 16. The main fan 28 is in the form of a spoked wheel having a hub, a number of radial blades or spokes 28a which act as turbine blades connected to a splitter ring 38 and a number of fan blades attached to the splitter ring. A secondary fan 40 is mounted upstream of the main fan and the blades of the fan extend only as far as the splitter ring of the main fan. The secondary fan 40 is mounted on a shaft 42 which is driven by a turbine 44. The shafts 26 and 42 can rotate either in the same or the opposite direction both to the shaft 20 and to each other.

The torque required to drive the main fan 28 is transmitted aero-dynamically through the blades 28a acting as turbine blades and sufficient torque is provided by the tur-

2

bine 44 through the shaft 42, to drive the secondary fan 40 and the main fan 28.

Both the main fan and the secondary fan are arranged to operate at sufficiently low tip speeds to ensure that the blade tip relative inlet flow Mach numbers are less than unity. This arrangement avoids undesirable tone noise which is associated with blade relative inlet flow Mach numbers of greater than unity.

In FIG. 2, in order to reduce the diameter of the bearing means 50, the main fan 28 is extended inwardly and is mounted on relatively small diameter bearing means 52 which are located between the compressor 16 and the secondary fan 40.

A principal difficulty with fans of low hub/tip ratio, as in the case of a conventional high by-pass ratio engine is that the tip runs faster than necessary for maximum efficiency if the root is to provide a satisfactory pressure rise. The provision of the secondary fan 40 both enables a satisfactory pressure rise to be obtained at the root of the main fan and the intake to compressor 16 to allow the tip speed of the main fan to be reduced, thus giving a reduced main fan white noise level.

In comparison with a conventional front fan three shaft engine of high by-pass ratio in which a low fan tip speed is required the present arrangement offers a number of advantages. A lower number of turbine stages is required; this is because the torque required to drive the low speed main fan 28 is transmitted aerodynamically through the blades 28a; e.g. a high by-pass ratio fan engine having eleven turbine stages can be reduced to an engine having five turbine stages. The secondary fan requires a small amount of torque which is produced by the moderately loaded turbine 44. This ensures a sufficiently low overall turbine noise level.

A higher compression ratio of the by-pass flow can be obtained and this is due to the presence of the secondary fan which reduces the whirl angle of the flow onto a ring of outlet guide vanes 46 in the region of the roots of the guide vanes, thus relieving the high outlet guide vanes root diffusion loading associated with the conventional low tip speed front fan engine design.

I claim:

1. A gas turbine engine having a by-pass duct and comprising:
  - 50 compressor means, combustion means and turbine means in flow series, said compressor means including a low pressure compressor and a high pressure compressor and said turbine means including a high pressure stage, an intermediate pressure stage, and a low pressure stage; a freely rotatable main fan extending completely across said by-pass duct; a rotatable secondary fan positioned upstream of said main fan and extending only partially across said by-pass duct; a first shaft for driving said high pressure compressor by said high pressure stage of said turbine means; a second shaft for driving said low pressure compressor by said intermediate pressure stage of said turbine means; and a third shaft for driving said secondary fan by said low pressure stage of said turbine means.
  - 60 2. An engine as claim in claim 1 in which said low pressure compressor has an outer casing, bearing means mounted on said outer casing, and said main fan being mounted on said bearing means.

3. An engine as claimed in claim 1 in which said low pressure compressor has an intake, and including bearing means located between said secondary fan and said intake, said main fan being mounted on said bearing means.

4. An engine as claimed in claim 1 including a splitter secured to said main fan, and in which said secondary fan is rotatable within said splitter.

5. An engine as claimed in claim 1 in which both the main fan and the secondary fan are arranged each to have a tip speed to give a blade relative inlet Mach number of less than unity.
